UNITED STATES PATENT OFFICE.

WALTER P. MAXIM, OF SOUTH PARIS, MAINE.

BRACKET.

SPECIFICATION forming part of Letters Patent No. 425,182, dated April 8, 1890.

Application filed January 2, 1889. Serial No. 295,192. (No model.)

To all whom it may concern:

Be it known that I, WALTER P. MAXIM, a citizen of the United States, residing at South Paris, in the county of Oxford and State of Maine, have invented an Improved Bracket; and I do hereby declare that the following is a full and exact description of the same, reference being had to the accompanying drawings, making part of the same.

My invention belongs to the class of brackets for supporting stagings, shelves, and other things; and the improvements relate to the construction whereby a compactly-folding bracket is made and one of extreme cheapness and convenience in use.

The improvements will be fully set forth in the following description and defined in the claims.

In the accompanying drawings, Figure 1 represents a side view of the bracket; Fig. 2, a top view of the same; Fig. 3, a front view thereof; Fig. 4, a rear view of the same; Fig. 5, a partial section in a plane indicated by the line 5 5 in Fig. 2, and Fig. 6 a side view 25 of the bracket folded for packing and transportation.

Like letters designate corresponding parts in all of the figures.

As a matter of economy and convenience in manufacturing, I prefer to make the brackets of similar pieces or bars of wood, which may be cut off from long strips dressed to like dimensions, though as to some features of my invention this construction is not essential. I have shown such pieces in the drawings. To construct a bracket of these pieces, I usually take two pieces A A for the upright, three pieces B B B for the projecting support, and two pieces C C for the brace. The two pieces each for the upright and brace are placed at their upper ends between the two ends, respectively, of the pieces forming the projecting support, as shown, separating all the parts to the extent of the thickness of the same. I connect the pieces for the upright and those for the projecting support by a single bolt or pin D, which not only connects the pieces, but furnishes a pivot on which they may turn for folding the parts together. In like manner I connect the pieces of the brace and of the projecting support by

a single bolt or pin E, which also serves as a pivot on which the parts may turn for folding. Then to complete the construction the lower end of the brace and that of the upright are removably connected by means of a piece G, forming a tenon or projection fastened between the two pieces C C, which compose the brace, so that this tenon may be inserted between the two pieces A A forming 60 the upright, and the descent of this tenon or projection is limited by a stop, which is preferably formed of a pin or bolt H, that also serves to hold the lower ends of the upright pieces together; but the brace-tenon can be 65 drawn upward and out of the space between the upright pieces for folding the bracket. The lower ends of the brace are mitered to the upright pieces, as shown, and not only abut against the same, but form shoulders to 70 assist the tenon G in wedging firmly over the bolt H.

The positions of the parts of the bracket when in use are shown in Fig. 1, and the positions of the parts when folded are shown in 75 Fig. 6.

For attaching the brackets to a wall an improved hook I is employed, made adjustable out and in to adapt it to different thicknesses of a wall or partition, so that it can be inserted into a simple aperture through the same. The construction for this purpose is fully shown in Fig. 5. The body or shank of the hook has a long slot or opening b in its rear end, and the lower edge of this slot has 85 a set of notches c c, which catch under the pivot D, that connects the upright and projecting support, though a separate pin or bolt might be used, which, however, is wholly unnecessary, as clearly seen by the drawings. 90 In connection with this notched slot embracing the pivot or pin, but having sufficient lateral play to allow the pivot to be shifted from one notch to another, there is an enlargement or stop d, which bears on the piece 95 and is made thick enough to not slip into the slot f, in which the hook is inserted. Thus the hook can be instantly shifted from one notch to another, and so be adjusted to suit the thickness of any part over which it is to 100 catch.

I claim as my invention—

1. A folding bracket composed of two separated upright pieces A A, three projecting horizontal separated support-pieces B B B, pivoted at one end to one end of said upright pieces, the ends of said upright pieces being arranged between the central and one of the outer horizontal pieces, two separated brace-pieces C C, pivoted at their upper ends to and between the outer ends of said horizontal pieces, the upper end of each brace-piece being arranged between the central and one of the outer of said horizontal pieces, and a locking-piece G, located between and secured to the lower ends of said brace-pieces, said locking-piece entering between and catching over a stop between the lower ends of said upright pieces, substantially as set forth.

2. A folding bracket having a bolt or pin therein, in combination with an adjustable attaching-hook for said bracket, said hook being formed with a slot or opening, through which said bolt or pin passes, said slot hav-

ing notches in one edge, with which said bolt or pin engages, substantially as set forth.

3. A folding bracket one of the folding parts of which has a slot f and a bolt or pin D across said slot, in combination with an adjustable attaching-hook I, located and sliding in said slot, said hook being formed with a slot b, through which said bolt or pin D passes, said slot b having notches c c, with which said bolt or pin engages, and said hooks having an enlargement or stop d, engaging the margins of said slot f, whereby said hook is retained in position, substantially as set forth.

In witness whereof I have hereunto signed my name in the presence of two subscribing witnesses.

WALTER P. MAXIM.
